CLAIM

The ornamental design for a work light, as shown and described.

DESCRIPTION

FIG. 1 is a perspective view of a first embodiment of a work light, showing my new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof; and
FIG. 8 is a bottom plan view thereof.
FIG. 9 is a perspective view of a second embodiment of a work light, showing my new design;
FIG. 10 is another perspective view thereof;
FIG. 11 is a front view thereof;
FIG. 12 is a rear view thereof;
FIG. 13 is a left side view thereof;
FIG. 14 is a right side view thereof;
FIG. 15 is a top plan view thereof; and
FIG. 16 is a bottom plan view thereof.

The broken lines in the drawings depict portions of the work light and form no part of the claimed design.

1 Claim, 16 Drawing Sheets
